DESIGN FOR A COLLAR RETAINING CLIP OR THE LIKE

William F. Becker, Elmhurst, N. Y.

Application February 15, 1936, Serial No. 61,195

Term of patent 7 years

To all whom it may concern:

Be it known that I, William F. Becker, a citizen of the United States, residing at 5 Toledo Street, in the county of Queens and State of New York, have invented a new, original, and ornamental Design for Collar Retaining Clips, or the like, of which the following is a specification, reference being had to the accompanying drawing, forming part thereof.

In the drawing, Figure 1 is a front elevational view of a collar retaining clip showing my new design; Figure 2 is a top edge view of same; and Figure 3 is a side elevation of the article.

I claim:

The ornamental design for a collar retaining clip or the like, as shown.

WILLIAM F. BECKER.
